UNITED STATES PATENT OFFICE.

WILLIAM H. DALTON, OF SALEM, MASSACHUSETTS.

HEATING UNIT.

Application filed November 1, 1921. Serial No. 512,080.

To all whom it may concern:

Be it known that I, WILLIAM H. DALTON, a citizen of the United States, and resident of Salem, county of Essex, State of Massachusetts, have invented an Improvement in Heating Units, of which the following description, in connection with the accompanying drawing, is a specification, like characters on the drawing representing like parts.

10 This invention relates to electric heating units and particularly to heating units of that type which are in the form of an elongated cylinder.

One of the objects of the invention is to provide a novel heating unit of this type which contains no metal except resistance wire so that the unit will heat metallic parts without danger of short-circuiting the heating current.

Another object of the invention is to provide a heating unit of this type in which the heating coil is connected to the lead wires without the use of binding screws or other metallic elements and in such a way that the 25 coils themselves are entirely relieved of any strain to which the lead wires may be subjected.

Another object of the invention is to provide an improved heating unit which is so 30 constructed that the heating coils may be either connected up in series or in parallel or in other ways to provide a unit of the wattage desire.

Other objects of the invention are to provide an improved heating unit which has various other advantages all as will be more fully hereinafter set forth.

In order to give an understanding of the invention I have illustrated in the drawings 40 some selected embodiments thereof which will now be described after which the novel features will be pointed out in the appended claims.

Fig. 1 is a longitudinal sectional view of 45 the shell or holder of my improved heating unit.

Fig. 2 is a perspective view of the shell.

Fig. 3 is an end view.

Fig. 4 shows the heating coil as it is prepared for introduction into the shell.

Figs. 5 and 6 show the manner in which the heating coil is electrically connected to the lead wires and the latter connected to

the shell in making up a heating unit having the lead wires extending from opposite ends 55 thereof.

Figs. 7 and 8 show the manner in which these operations are carried out in making a heating unit in which the lead wires extend from the same end. 60

Fig. 9 shows an embodiment of the invention where the coils are arranged in parallel.

Fig. 10 shows an embodiment of the invention where two or more heating units are 65 arranged in tandem.

My improved heating unit comprises a shell or holder 1 which is preferably cylindrical in shape, although the exact shape is not essential to the invention. This shell or 70 holder 1 is made of material which has insulating properties and which is also highly refractory and is a conductor of heat. The shell 1 is provided with one or more longitudinal bores 2 extending from one end to the 75 other thereof and in which the heating coils may be placed. The shell is also provided with a recess 3 at each end with which the bores 2 communicate, each recess having a sufficient diameter so that all the bores 2 80 may open therewith. The formation of this recess provides a flange portion 4 at each end of the shell which constitutes the wall of the recess.

In the construction illustrated the shell is 85 provided with four coil-receiving bores 2 although the number is immaterial so far as the invention is concerned and may be varied without departing therefrom.

The heating coil of the unit is indicated at 90 5 and the lead wires at 6. The bores 2 are utilized both for securing the lead wires to the shell 1 and for the reception of the heating coil or coils 5.

In order that the heating coils 5 may 95 function properly it is essential that the turns thereof should be correctly spaced and to provide for maintaining this spacing both while the coils are being introduced into the bores and while the unit is being used I propose to provide a strand-receiving member 100 which extends the length of the coil and which takes any longitudinal strand thereof. This strand-receiving member is shown at 7 and may be in the form of a cord or flexible connection preferably of insulating

material and which is connected at its ends to the ends of the coil as shown at 8. With this arrangement any longitudinal strain will be taken by the member 7 and not by 5 the coil.

In assembling the coil 5, lead wires 6 and shell 1 to make a complete unit I propose to first anchor the end of the lead wires in one or more of the bores 2 and then to 10 draw the coil through another bore or bores and subsequently connect the ends of the coils to the lead wires.

Figs. 5 and 6 show how this may be done in the case of a unit where the lead wires

15 extend from opposite ends thereof. The lead wires 6 are shown as stranded wires, preferably untwisted stranded wires, and one end 9 of each wire is inserted into the end of one of the bores 2, as shown in

20 Fig. 5. If the lead wires extend from opposite ends of the unit then the two ends 9 of the lead wires may be inserted into opposite ends of the same bore. These lead wires are anchored in the bore in some

25 suitable way as for instance by filling the latter with cement 10 and in order to make a good connection the end of each lead wire may be bent or shaped to form an enlarged portion 11. The ends of the lead wires are

30 separated from each other so there is no electrical connection between them. After the lead wires have been thus anchored in the shell 1 then the coil 5 is drawn into another bore as shown in Fig. 5. The coil

35 is made with straight ends 12 of considerable length and the coil portion thereof will be of a length equal to that of the bore 2. The presence of the connection 7 enables the

40 heating unit to be drawn into the bore without disturbing the relative position of the turns of the coil.

After the heating unit has been located in the bore, as shown in Fig. 5, then the ends 12 thereof are twisted with the projecting 45 ends of the lead wires so that a stranded wire is formed in which some of the strands pass into the end of a bore and terminate therein and another strand extends through the bore and constitutes the circuit for the heating current. If desired, the strands of the lead wires 6 may be of the same material as that used in the coil 5 or they may be of different material so long as they have 50 proper conducting properties.

55 After the ends of the coil have thus been twisted into the strands 6 then suitable insulation 13 is applied to the projecting ends as shown in Fig. 6, the insulation extending clear into the recesses 3.

60 A heating unit having this construction has an exterior formed entirely of insulating material so that it can be used in any location and placed in direct contact with any object without danger of short circuit-

ing the heating current. The only metallic portions of the unit are the lead wires 6 and the coil 5 and these are thoroughly protected by insulation.

In Figs. 7 and 8 I have shown an embodiment of the invention where both the lead wires extend from the same end of the unit. The process of making the unit, however, is substantially as above described, that is, the ends of the untwisted stranded lead wires are inserted into the ends of 75 two bores 2 and secured therein, as shown in Fig. 7 and the coil 5 is then drawn through one bore and back through another bore and the ends 12 thereof are then twisted into the lead wires. Insulation is 80 then applied to the twisted wires thus producing a heating unit in which the two lead wires extend from the same end and in which a double heating coil is used with the two turns thereof in series.

85 In Fig. 9 I have illustrated an embodiment of the invention in which two coils 5 are used to be arranged in multiple. The construction of Fig. 9 is similar to that 90 shown in Figs. 5 and 6 except that there are two heating coils instead of one and the ends of both coils are twisted into the lead wires 6.

In Fig. 10 I have shown a different arrangement in which two shells are arranged 95 in tandem from end to end and in which longer heating coil is drawn through both shells thus producing a heating unit of 100 double length. In other respects the construction shown in Fig. 10 is similar to that above described.

I claim.

1. A heating coil comprising a shell of insulating material having a relatively small bore extending from one end to the other 105 thereof, a heating coil within said bore, a lead wire connected to each end of the coil outside the bore, and means other than the coil for anchoring each lead wire to the shell.

110 2. In a heating unit, the combination with a shell of insulating material having a bore extending from one end to the other thereof, each end of the shell being provided with a recess with which the bore communicates, of a heating coil within said bore, a lead wire connected to each end of the coil within one of the recesses, and means other than the coil for anchoring each lead wire to the shell.

115 3. A heating unit comprising a shell of insulating material having a bore extending from one end to the other thereof, two lead wires anchored to the shell, and a heating coil occupying said bore and having each 120 end twisted into an extended portion of one of the lead wires.

120 4. A heating unit comprising a shell of

insulating material having a bore extending therethrough, two lead wires anchored to the shell, a heating coil occupying said bore and having each end twisted into an extended portion of one of the lead wires, and insulation covering the portions of the lead wires with which the ends of the heating coil are twisted.

5. A heating unit comprising a shell of insulating material having a plurality of bores extending from one end to the other thereof, two lead wires each having its end entering and anchored in one of the bores, a heating coil occupying another bore and having its

ends twisted into the portions of the lead wires which are situated exterior to the shell.

6. A heating unit comprising a shell of insulating material having a bore extending from one end to the other thereof, two lead wires anchored to the shell, and a heating coil occupying said bore and having each end projecting beyond the shell, said ends being twisted into the extended portions of the lead wires.

In testimony whereof, I have signed my name to this specification.

WM. H. DALTON.
